UNITED STATES PATENT OFFICE.

ARTHUR S. BEMIS, OF CLEVELAND, OHIO, ASSIGNOR TO NATIONAL CARBON CO. OF CLEVELAND, OHIO, A CORPORATION OF NEW JERSEY.

ROTARY ELECTRIC FURNACE.

1,105,175.

Specification of Letters Patent. Patented July 28, 1914.

Application filed January 22, 1912. Serial No. 672,618.

To all whom it may concern:

Be it known that I, ARTHUR S. BEMIS, a resident of Cleveland, in the county of Cuyahoga, in the State of Ohio, have invented 5 new and useful Improvements in Rotary Electric Furnaces, of which the following is a clear and exact description.

This invention relates to rotary electric furnaces.

10 One of the objects of my invention is to construct a furnace in which there is no constricted portion in the electric heating zone to hinder the flow of material through the furnace.

15 Another object of my invention is to construct a furnace that is self feeding, easy to operate, and at the same time of high efficiency.

20 Other advantages will appear in the following description particular reference being had to the drawings in which:

Figure 1 is a sectional elevation taken on the section line A—A of Fig. 2. Fig. 2 is a section taken on the line B—B of Fig. 1. 25 Fig. 3 is a top view of the furnace shown in Fig. 1 with the hopper removed.

Referring to Fig. 1 the outer walls of the furnace are indicated at 1. Inside of these outer walls are inner walls 2 extending upward from the base of the furnace. The inner walls 2 are joined at the base to the outer walls 1. Extending downward from the top of the furnace are other interior walls 3. These are joined to the outer walls 1, by means of the top portion 4. This top portion is shown as being flat although it may be made arched shaped if desired. The inner walls 3 are supported by stay rods 5 fastened to standards 6 at the outside of the 30 furnace. The walls of the furnace may be made of firebrick though they may be made of any other heat resisting material. If exceedingly high temperatures are reached in the furnace, it would be preferable to construct the walls in the vicinity of the heating 35 zone of carbon or carborundum.

On top of the furnace and at one side is a tower 7 for supporting the upper electrode. This tower may be made of materials similar 40 to that of the other furnace walls. Beneath the furnace is a bin 8 composed preferably of firebrick though it may be made of other material. This bin receives the treated material as will be fully explained later.

45 The carbon wheel or platform 9 is sup-

ported between the inner walls 3 and 2 by a shaft 10, supported in a lower step bearing 11 and an upper bearing 12. The bearing 11 is supported by a member 11' held by the furnace walls. The member 11' is 60 preferably made of iron. The wheel 9 is preferably fastened to a conducting bracket support 13 which is keyed or otherwise fastened to the shaft 10. The wheel 14 is shown on the shaft 10 for transmitting 65 power to the shaft to rotate it.

Extending through the tower 7 is a hollow carbon electrode 15 supported by a member 15' which may be raised or lowered by hand screws 16, 17 fastened to a 70 plate 18 on top of the tower 7. By this arrangement the hollow electrode may be raised and lowered to regulate the current to thereby control the degree of heating. I have shown only one hollow electrode, but it 75 is obvious that a plurality of these may be used and spaced at various places around the furnace. It is advisable to make the opening in the lower part of the electrode 15 divergent as shown, to prevent the material 80 from clogging therein.

One terminal 19 of a source of E. M. F. is connected to the tubular member 15 and the other terminal 19' is connected to the lower bearing support 11'. In order to increase the contact surface a gland 20 surrounds the shaft 10 and is supported on the member 11' by metallic standards 21. The gland is packed with graphite and serves as a means for conducting part of the current 90 to the shaft. The remainder passes to the shaft through the bearing 11. If desired a copper brush may conduct the current to the shaft 10.

In order to prevent air from reaching the 95 interior of the furnace and causing the carbon wheel 9 and the electrode 15 to be consumed the inner walls 2 have two concentric rings 22, 23 spaced apart so as to leave a channel therebetween. Another concentric 100 ring 24 depends from the wheel 9 and extends into the channel between the rings 22 and 23. The space between these two rings is also filled with powdered graphite or other suitable material. By this means the furnace is substantially air tight. However, if desired the furnace can be filled with a gas such as illuminating gas, hydrogen, nitrogen or any other inert gas. A pipe 31 having a valve 32 is shown for this purpose. 105 110

It may be advisable to use a liquid jacket to cool the upper part of the electrode 15 and I have shown a jacket 33 for this purpose.

5 The operation of the furnace is as follows: The granular material is fed into the furnace through the hopper 27 down through the carbon electrode 15. The charge will initially spread out over the wheel 9 as it 10 emerges from the electrode in the shape of a frustum of a cone, and on account of the current going through a constricted portion of the cone is intensely heated in a very short time. The carbon wheel 9 is slowly 15 revolved by means of the pulley 14, and as it moves fresh material is fed down by means of its own weight onto the carbon wheel, which is in turn heated to the desired point. By this means it is seen that the 20 charge is heated to the desired point and then is removed from the heated region and a fresh supply takes its place. The charge forms a row or ridge with slanting sides, and the treated part is finally pushed off of 25 the carbon wheel 9 by means of a carbon slab 28 which may be projected from the walls 1 as shown in Fig. 2. This slab may be positioned at any place in the circumference of the furnace. The treated material falls into 30 the bin 8 where it may be removed at intervals by pulling out the member 29 or by any other well-known means. A plurality of slabs 28 would be used if a plurality of electrodes 15 were employed. It is obvious 35 that other means may be employed to accomplish this purpose. If found desirable the treated material in the bin 8 may be cooled by a liquid circulated in the pipes 30.

The carbon wheel 9 can be formed in one 40 disk if desirable, though I prefer to form it in sectors as shown in Fig. 2. However, it can be constructed in any manner without departing from the scope of my invention.

The current used in this furnace may be 45 either direct or alternating. The path of the current is from one connection 19 through the carbon electrode 15, and also through the charge therein until the base of the electrode is reached. Here the current 50 passes entirely through the pile of material just emerged from the electrode. Then it passes through the carbon wheel 9 to the conducting bracket 13, shaft 10, bearing 11 and member 11' to the lower connection 19'. The current also passes to the 55 terminal 19' through gland 20, support 21 and member 11'.

The furnace is particularly well suited for 60 the calcination of granular carbon and for the manufacture of graphite, though it may be used for heating any other material to any desired temperatures. Any material that is a conductor of electricity and that will flow through the tube 15 can be treated 65 in this type of furnace.

The temperature reached can be controlled by regulating the current passing through the furnace and also by regulating the speed of rotation of the wheel. If the wheel is rotated at a very slow rate the temperature of course will be higher than if it were rotated at a faster rate. The current sent through the furnace can be regulated by any means well known in the art, and it can also be regulated by raising or lowering the electrode 15 by means of the hand screws 16, 17 as has been previously explained. 70 75

This type of furnace will not become clogged as there is no constricted portion in the heating zone and as the treated material is positively and forcibly removed by the rotating wheel 9. This is an important advantage as it has been found that electric furnaces having a constricted portion in the electric heating zone are liable to become 80 clogged and the removal of the treated material below this constricted portion does not always cause the charge above to feed down. I have eliminated this difficulty in my type of furnace. It is not necessary that the carbon wheel move continuously. It may move intermittently so that the charge is fed downward onto the wheel in a series of steps. It is also not necessary to arrange the wheel in a horizontal position. It could 85 90 equally as well be inclined.

Having described my invention what I claim is:

1. The method of heating material which consist in feeding it into a space whereby 100 it is formed into a pile, passing an electric current through the peak, and then moving it in a direction substantially at right angles to its perpendicular axis.

2. The method of heating granular material which consists in feeding it into a space whereby it is formed into a pile, passing an electric current through the peak of the pile, and then moving it substantially at right-angles to the general direction of current 110 flow.

3. In an electric furnace, furnace walls, a lower electrode, said walls and electrode being relatively rotative about a vertical axis, means for feeding the material onto the 115 electrode and means whereby current is transmitted through the material to the electrode as it emerges from said feeding means.

4. In an electric furnace, an electrode rotatable about a vertical axis, means for feeding material thereon, means whereby current is transmitted through the material to said electrode as it emerges from said feeding means, and means for rotating said electrode. 120 125

5. In an electric furnace, an electrode rotatable about a vertical axis, a hollow electrode for feeding material thereon, and means for rotating said electrode. 130

6. In an electric furnace, a conducting member, a hollow electrode for feeding material onto said member and for transmitting current through the material to said member, and means for moving the member so that the material is placed in a row thereon.
7. In an electric furnace, a conducting member, a hollow electrode for feeding material onto said member, means for moving the member so that said material is placed in a row thereon, and means for forcing the material off the member.
8. In an electric furnace, outer inclosing walls, a rotating electrode supported on a vertical axis inside the furnace, a hollow electrode extending through the top of the furnace and a hopper for feeding the furnace charge through the hollow electrode onto the rotating electrode, and a member for removing the treated charge from the rotating electrode when it is moved out of the heating zone.
9. In an electric furnace, outer inclosing walls, a horizontal rotating electrode, a hollow electrode extending through the top of the furnace, a hopper for feeding the furnace charge through the hollow electrode onto the rotating electrode, means for removing the treated charge and means for preventing air from entering the interior of the furnace.
10. In an electric furnace, an inner and an outer furnace wall, said inner wall being separated into upper and lower parts, an electrode between said parts and means for rotating the electrode about a vertical axis.
11. In an electric furnace, a furnace wall separated into upper and lower parts, an electrode therebetween a packing material between the electrode and said parts to prevent the passage of air, and a second furnace wall outside of the inner wall and spaced therefrom.
12. In an electric furnace, an inner and an outer furnace wall, said inner wall being separated into upper and lower parts, an electrode located between said parts, means for rotating said electrode about a vertical axis, a hollow electrode extending toward said rotatable electrode and means for feeding the furnace charge therethrough onto the rotatable electrode.
13. In an electric furnace, an outer wall, an inner wall separated into upper and lower parts, said inner and outer walls being spaced apart, a rotatable electrode extending between said upper and lower parts and means to prevent air from passing between the electrode and said parts into the space between the inner and outer walls.

In testimony whereof I have hereunto signed my name.

ARTHUR S. BEMIS.
